UNITED STATES PATENT OFFICE.

ROBERT W. STOGNER, OF HARTSVILLE, SOUTH CAROLINA.

WAVE-SETTING DEVICE.

Application filed September 30, 1927. Serial No. 223,124.

This invention relates to wave setting devices for hair dressing purposes, and more particularly to the type adapted for use after a permanent wave has been given, in order 5 to set the wave.

In certain hair dressing processes heretofore in use, after a permanent wave has been given, it is necessary to press the hair firmly against the head, in order to set the wave. 10 No instrument has been provided for conveniently setting the wave. It is therefore one of the principal objects of the present invention to provide a wave setting device which will perform this operation in a very 15 satisfactory manner.

It is another object of the invention to provide a simple and efficient wave setting device, which will at the same time be inexpensive to manufacture and simple in 20 operation.

Other objects and features of novelty will be apparent as the description proceeds, when taken in connection with the accompanying drawings, in which:

25 Fig. 1 is a perspective view of the device in operation, showing the application of the wave setting device to the human head;

Fig. 2 is a side elevation of the wave setting device;

30 Fig. 3 is a cross section along the line 3—3 of Fig. 2; and

Fig. 4 is a perspective view of a foldable form of the invention showing the head engaging portion thereof in an intermediate 35 position by the dotted line portions of this figure.

Referring more particularly to the drawings, the wave setting device comprises a member indicated generally at 10, having a 40 handle portion 11 suitably shaped to fit the hand, and an outer or head engaging portion 12, having a smooth edge 13 which is shaped to closely conform to the contour of the human head.

45 The member is generally constructed of flat material of any desired kind, although the device need not necessarily be flat. Various materials may be used, such as hard rubber, metal, fiber, or wood.

50 In the form shown in the drawings, the member 10 is in the shape of an elongated letter S, the handle forming one curved end and the head engaging portion forming the

reversely curved end. As shown in Fig. 3, the head engaging portion is preferably 55 tapered so that the edge which presses the hair against the head is comparatively thin, but at the same time is perfectly smooth. The curvature of the head engaging portion to closely fit the contour of the head is quite 60 important, as it permits much better results than have been heretofore accomplished by other devices. The thin edge 13 is an added refinement, as by this means still better results can be obtained.

In the form shown in Fig. 4 the member 10 consists of two parts, as the handle 11 and the curved head engaging portion 12 are made separately, and pivoted together by a pin 14. The handle portion 11 is bifurcated 70 as at 15 and the outer portion 12 is inserted between the bifurcations and secured in place by this pivot. The handle 11 is also provided with an elongated groove 16 which is adapted to receive the edge 13 when the 75 parts are folded together about the pivot 14. This groove protects the smooth edge of the outer portion 12 and also permits the entire device to be folded into a very compact 80 article.

The portion 12 is continued rearwardly beyond the pivot pin to form an extension 17, in which a stop pin 18 is mounted. When the folded device is opened out into its operative position, the pin 18 lodges in slot 19 85 provided in the handle bifurcations, and prevents the two parts from pivoting past the operative position. In other words, the pin 18 and the slot 19 serve to locate the folding member in its unfolded or operative position. 90

While specific embodiments of the invention have been shown and described in comparative detail, the invention is not limited to the exact construction shown and described, but includes such limitations as come 95 within the scope of the appended claims.

Having thus described the invention, what is claimed as new and desired to be secured by Letters Patent is:

1. A wave setting device for hair dressing purposes comprising a member having a handle portion and a hair dressing portion, said last mentioned portion being longitudinally curved to uniformly engage the upper strands of the user's hair when applied thereto and having a smooth narrow 100 105

edge for pressing the hair against the head to set a wave.

2. A wave setting device for hair dressing purposes comprising an elongated substantially flat member one end portion of which is enlarged and shaped to form a handle, the other end portion comprising a hair dressing member, said member being curved longitudinally to uniformly engage the up-

per strands of the user's hair when applied thereto, and being substantially wedged shaped in cross section with a smooth rounded relative thin edge for pressing the hair against the head to set a wave.

In testimony whereof I hereunto affix my signature.

ROBERT W. STOGNER.
